DESIGN FOR A WASTEBASKET

Martha H. Connor, Baltimore, Md., assignor to Owens-Illinois Can Company, Wilmington,
Del., a corporation of Delaware

Application September 30, 1936, Serial No. 65,087

Term of patent 7 years

To all whom it may concern:

Be it known that I, Martha H. Connor, a citizen of the United States and residing at Baltimore, in the State of Maryland, have invented a new, original, and ornamental Design for a Wastebasket, of which the following is a specification, reference being had to the accompanying drawing, forming a part thereof.

The drawing is a perspective view of a wastebasket showing my new design. The dominant feature of the design is the series of helical pin stripes provided on the outer surface of the waste basket as shown. The stippled areas represent a color different from the remaining areas.

I claim:

The ornamental design for a wastebasket, substantially as shown and described.

MARTHA H. CONNOR.
